UNITED STATES PATENT OFFICE.

CLYDE J. COLEMAN, OF NEW ROCHELLE, NEW YORK.

COMBINED MOVING-PICTURE MACHINERY AND PHONOGRAPHIC APPARATUS.

1,312,103.

Specification of Letters Patent.

Patented Aug. 5, 1919.

Application filed August 21, 1915. Serial No. 46,629.

To all whom it may concern:

Be it known that I, CLYDE J. COLEMAN, a citizen of the United States, and a resident of New Rochelle, county of Westchester, and

5 State of New York, have invented certain new and useful Improvements in Combined Moving-Picture Machinery and Phono-graphic Apparatus, of which the following is a specification.

10 My invention relates to synchronized moving picture apparatus and phonographic apparatus.

One object of my invention is to mechanically reproduce sounds in true synchronism 15 with the projection of images portraying the original production of the same sounds. This object is attained by using a phonograph record on a reproducing machine and simultaneously passing a correlated series of 20 pictures through a projecting machine, the two machines being operated in true synchronism whereby the sounds and images mutually coöperate to interpret one another.

Another object is to secure realism in the 25 simultaneous production of sounds and images. This is attained by positioning the sound-producing mechanism in such close proximity to the images as to produce the illusion that the sound emanates from the 30 image itself. This object is attained by positioning the sound-producing machine so that the sound passes through or very close to the edge of the screen onto which the images are projected.

35 Another object is to correlate the two machines so that they may be simply and accurately synchronized. This object is attained by avoiding the complexities arising from synchronizing widely separated 40 machines by mounting them so that they are operated from a common source of mechanical power, but the operation of one machine does not in any way impair the operation of the other. Both machines are 45 mounted behind a translucent screen and the images are projected through the screen and the sound passes through it or around it.

Other and further objects and advantages 50 will appear from the description of my invention taken in connection with the drawings forming a part of this specification, and will be pointed out in the claims.

In the single figure of the drawings a preferred form of my invention has been 55 illustrated. I do not, however, intend that my invention shall be limited to the precise

form disclosed by this specification, but intend that it shall include such modifications as may occur to those skilled in the art, and that my invention shall be defined only by 60 the hereunto appended claims.

In the device shown in the figure, a moving picture projecting device 1 is mounted upon an ordinary pedestal 2 and upon this pedestal is mounted a source of light 3 from 65 the lens 4 of which the light is passed into the projecting mechanism. The light rays, after passing through the film, leave the projecting mechanism through a second lens 5 and pass onto the translucent defining 70 screen 6. This screen is made translucent because it is intended that the picture shall be viewed from the opposite side of it from that on which the projecting mechanism is situated. An electric motor 7 receives electric power from the source 8 through the speed-controlling rheostat 9 and a worm 10 on a motor shaft 11 drives a worm wheel 12 which is keyed onto the moving picture mechanism driving shaft 13. On this driving shaft there is keyed a second worm 14. A bracket 16 is positioned on the side of the moving picture machine and has mounted in bearings fixed thereon a shaft 17. The lower end of this shaft 17 carries a wheel 18 85 which coöperates with the wheel 14. The upper end of this shaft carries one member 19 of a coupling.

Mounted upon the upper end of the moving picture machine is a sound-reproducing 90 mechanism, or phonograph 20. Between the moving picture machine and the phonograph there is positioned sound-deadening or vibration-absorbing material 21 to prevent the vibration of the moving picture machine 95 from being transmitted through the sound-reproducing mechanism into the sound-magnifying horn. The phonograph driving shaft 22 has mounted upon it a wheel 23. Mounted upon the phonograph casing is a 100 bracket 24 in which is journaled a shaft 25. On the upper end of this shaft 25 is a wheel 26 which coöperates with the wheel 23. The lower end of this shaft 25 carries a coupling member 27, and adjoining the coupling members 19 and 27 there is sound-deadening and vibration-absorbing material 28. It will be seen, therefore, that there is no mechanical connection between the phonograph and the moving picture machine which is not provided with means for preventing any of the vibrations of the moving picture machine 110

from interfering with the proper operation of the sound-reproducing mechanism. The phonograph has the ordinary sound box 29, and mounted upon the bracket 30 is a sound-magnifying horn 31. This horn extends to the screen 6 and its exit opening registers with the opening 32 in the screen, said opening, as shown, being above the picture portion of the screen; and both the opening 32 5 and the exit opening of the horn may be of small area relatively to the picture portion of the screen. It will be seen, therefore, that when a picture is reproduced on the screen by driving the kinetoscope by means of 10 the motor 7, the phonograph by reason of being mechanically connected to the moving picture machine, is driven in exact synchronism and the source of the sound is so close to the point where the images are 15 defined by the screen that an illusion is produced in the mind of the person viewing the images whereby it appears that the sound emanates from the images themselves. It will be seen that by positioning the moving 20 picture machine behind the screen I am enabled to connect the phonograph directly therewith by mechanical means and thereby secure absolute synchronism without experiencing the difficulties ordinarily encountered 25 30 when it is attempted to synchronize widely separated machines. Both the moving picture machine and the phonograph are concealed by the screen.

Other means for securing synchronous operation of phonographic and moving picture machines are disclosed in applications for patent filed by me for improvements in synchronizing mechanism, Serial Number 46,630, filed Aug. 21, 1915, and for improvements in combined kinetoscopic and phonographic apparatus, Serial Number 46,628, filed Aug. 21, 1915.

Having thus described my invention, what I claim as new and desire to secure by Letters Patent, is:—

1. In an apparatus of the class described, the combination of a translucent screen, a sound reproducing machine, a moving picture machine arranged behind said screen, 50 one of said machines being mounted on the top of the other, means for driving one from the other, and means for preventing the transmission of vibration from one to the other.

2. In apparatus of the class described, the 55 combination of a translucent screen, a moving picture machine having a large angle of projection arranged behind the screen to project pictures thereon, a sound producing machine mounted on said moving picture 60 machine, means for delivering the sound produced by said sound producing machine into the space in front of said screen at a point substantially in the plane of said screen and at the apparent point of origin 65 of the sound, means for driving said machines in synchronism, and means for preventing the transmission of vibration from one machine to the other.

3. In an apparatus of the class described, 70 the combination of a translucent screen, a moving picture machine located behind said screen and arranged to project moving images thereon, a reproducing phonograph located behind said screen, said screen having 75 an opening therein, and a sound-conducting tube extending from said reproducing phonograph substantially to said screen to the side of the rays projected from the said motion picture machine upon said screen and 80 delivering the sounds produced through said opening into the space in front of said screen at a point substantially in the plane of said screen and at the apparent point of origin 85 of the sound.

4. In an apparatus of the class described, the combination of a translucent screen, a moving picture machine located behind said screen and arranged to project moving images thereon, said screen having an opening 90 outside of the picture portion thereof, a sound-reproducing machine located behind said screen, a sound conveyer extending from said sound-reproducing machine substantially to said screen to the side of the rays 95 projected from the said motion picture machine upon said screen and delivering the sound produced by said sound-reproducing machine through said opening into the space in front of said screen at a point substantially in the plane of said screen and at the apparent point of origin of the sound, the exit of said sound conveyer being of small area relatively to the picture portion of said screen.

In testimony whereof, I have signed my name to this specification.

CLYDE J. COLEMAN.
